(57) **CLAIM**

I claim the ornamental design for a folder, as shown and described.

DESCRIPTION

FIG. 1 is a front/right/top perspective view of a first embodiment of the folder;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and

FIG. 7 is a right side elevational view thereof

FIG. 8 is an alternate front/left/top perspective view thereof, with the front surface shown in an alternate position curled from upper right to lower left.

FIG. 9 is an alternate front elevational view thereof, with the gusset shown in an alternate position, extended out.

FIG. 10 is a front/right/top perspective view of a second embodiment of the folder;

FIG. 11 is a front elevational view thereof;

FIG. 12 is a rear elevational view thereof;

FIG. 13 is a top plan view thereof;

FIG. 14 is a bottom plan view thereof;

FIG. 15 is a left side elevational view thereof; and

FIG. 16 is a right side elevational view thereof.

FIG. 17 is an alternate front/left/top perspective view thereof, with the front surface shown in an alternate position, curled from upper right to lower left.

FIG. 18 is an alternate front elevational view thereof, with the gusset shown in an alternate position, extended out;

FIG. 19 is a front/right/top perspective view of a third embodiment of the folder;

FIG. 20 is a front elevational view thereof;

FIG. 21 is a rear elevational view thereof;

FIG. 22 is a top plan view thereof;

FIG. 23 is a bottom plan view thereof;

FIG. 24 is a left side elevational view thereof; and

FIG. 25 is a right side elevational view thereof.

FIG. 26 is an alternate front/left/top perspective view thereof, with the front surface shown in an alternate position, curled from upper right to lower left; and,

FIG. 27 is an alternate front elevational view thereof, with the gusset shown in an alternate position, extended out.

1 Claim, 15 Drawing Sheets
